UNITED STATES PATENT OFFICE

2,452,926

METHOD OF GRINDING PROPELLER SHANKS

Frederick A. Gruetjen, Milwaukee, Wis., assignor to A. O. Smith Corporation, Milwaukee, Wis., a corporation of New York

Application July 13, 1945, Serial No. 604,771

2 Claims. (Cl. 51—290)

1

This invention relates to a method of grinding propeller shanks.

Modern aircraft propeller blades have shanks of various shapes, usually embodying a plurality of external and internal circumferential ribs, shoulders and grooves for accommodating balancing weights and for securing the blade to the hub attachment. In order to preserve the proper dynamic balance of the blade in operation and prevent unbalance of the propeller, the internal and external surfaces of the shank have to be machined or ground with considerable accuracy relative to the longitudinal center line of the blade.

In practice in the best known propeller factories, it has been the custom to mount the blade in a shuttle which is rotated on rollers in a semi-centerless grinding machine with rotary grinding wheels for grinding the inside and outside of the shank, respectively. Shuttles are extremely expensive, and the loading and unloading of blades therein is a long and tedious operation greatly reducing the capacity of the plant unless a large number of shuttles, machines and skilled workmen are available. Furthermore, the rotation of the shuttle becomes inaccurate in the event dirt or foreign material collects upon the supporting rollers.

The object of the present invention is to eliminate the use of shuttles and provide a simpler and less costly method of grinding the shanks.

Another object is to provide a more accurate method for grinding propeller shanks.

The practice of the invention is illustrated in the accompanying drawings in which:

Figure 1 is a longitudinal central section taken through the shank end of a propeller blade after rough machining and prior to grinding;

Fig. 2 is a side elevation of a hollow spindle grinder with parts in section and showing the mounting of a blade preparatory to grinding the inside of the shank;

Fig. 3 is a perspective view showing the blade mounted on an expanding chuck in a standard lathe;

Fig. 4 is a longitudinal central section taken through the shank end of the blade after completion of the grinding operation; and

Fig. 5 is a similar section after threading.

The blade 1 to be ground is hollow and has a generally cylindrical shank 2 merging into the air foil body of the blade, and a tip centering projection 3. The projection 3 has a tapered centering punch mark or recess 4 located in its tip and on the longitudinal center line of the blade as determined in a vertical balancing machine for de-

2

termining the center of gravity. The shank of the blade is ordinarily machined inside and outside on the measured longitudinal center line of the blade prior to balancing, and leaving an allowance for grinding on all surfaces.

The blade thus fabricated is mounted in a hollow spindle grinder 5 as shown in Fig. 2. The hollow spindle 6 of the grinder has a chuck or collet 7 at its forward end for centrally securing the cylindrical shank 2. The jaws of the chuck 7 should grip the shank at about the longitudinal mid-point of the proposed internal grinding operations.

The centering projection 3 at the tip of the blade is engaged by a spring pressed centering pin 8 which is rotatably mounted in a stationary post 9.

The grinder 10 comprises a small high speed contour grinding wheel 11 mounted on a shaft 12 driven by a motor 13 on a pedestal 14 which can be moved longitudinally toward and away from the blade. The grinding wheel 11 enters the shank and engages the inside surface eccentrically of the shank to effect grinding of the same. The wheel 11 is replaceable by wheels of different shapes and sizes to enable the grinding of different types of shanks. The inside grinding may be accomplished with a single wheel or different wheels may be employed.

The grinding wheel 11 is fed longitudinally in the shank as it rotates, and the rotation of the shank taken with the eccentric mounting of the wheel 11 relative to the center line of the shank effects a relative grinding feed circumferentially of the shank.

The grinding operation illustrated provides an end shoulder 15, a cylindrical surface 16 for threading, a grooved relief 17 at the inner end of 16, and an inner shoulder 18 for retaining the balancing weights. Different types of blades will have a different contour.

After the inside grinding is completed, the blade is removed from the machine of Fig. 2 and mounted in the machine of Fig. 3 which may be a lathe 45 as shown or a grinder. Here the blade is supported for rotation on an expansible mandrel 19 which engages the inside of the shank and thereby accurately locates the blade for rotation on its longitudinal center line. The mandrel should be of a type that will not mar the inside surface of the shank. A grinding wheel 20, mounted on a pedestal 21, is fed to and along the outside of the shank as the latter rotates.

Usually two separate grinding wheels are employed. The first grinding wheel trues the cylin-

cylindrical surface of the shank from the end to a suitable distance beyond the cuff ring 22. The second grinding wheel is contoured to provide the grease seal relief 23. Different types of blades will require different outside shapes for the shanks.

By employing the method above outlined, the production of blades is greatly increased with less equipment and labor than under former practices which employed a shuttle grinder. The accuracy of grinding is more readily maintained than is possible with shuttles, since all of the rotary bearings are enclosed and protected from dirt, and the mounting of the blade is ordinarily more accurate.

Various practices may be employed within the scope of the invention as set forth in the accompanying claims.

I claim:

1. The method of grinding hollow propeller blade shanks, comprising mounting the blade in a hollow spindle grinder with a chuck or collet gripping the shank at about its mid-portion, centering the blade in the spindle by applying an index holder to the tip of the blade, grinding the inside contour of the shank to finished dimensions, removing the blade and mounting the same upon an expansible rotary mandrel engaging the accurately ground inside surface of the shank, and

then grinding the outside of the shank to accurate dimensions.

2. The method of grinding hollow propeller blade shanks, comprising mounting the blade in a hollow spindle grinder with a chuck or collet gripping the shank, centering the blade in the spindle by applying an index holder to the tip of the blade, grinding the inside contour of the shank to finished dimensions, removing the blade and mounting the same upon an expansible rotary mandrel engaging the accurately ground inside surface of the shank, and then grinding the outside of the shank to accurate dimensions.
